UNITED STATES PATENT OFFICE

EDWARD P. COLE, OF CHICAGO, ILLINOIS

INCINERATOR

Application filed May 12, 1928. Serial No. 277,178.

My invention relates to devices for burning garbage and the like wherein there are superposed compartments, the lower one of which serves to heat and dry the garbage which is preliminarily placed in the upper compartment and thereafter transferred to the lower compartment for final combustion.

The principal objects of my invention are to provide an improved device of this character having a combustion chamber and a drying compartment, in the latter of which garbage is exposed to and dried by the heat from the combustion chamber and then conveniently transferred to and used as fuel in the combustion chamber; to construct the drying compartment so that it may function as a combustion chamber; to provide a draft outlet which permits circulation of air through the drying compartment as well as the combustion chamber; to regulate the communication of each compartment with the draft outlet or stack; to control the circulation of heated gases from the combustion chamber through the drying chamber; to prevent escape of odor from the garbage in the incinerator; and in general to provide a simple, convenient and effective device for drying and burning garbage and the like.

On the drawing:

Fig. 1 is a front view of the incinerator with a portion at one side broken away to show a fragmentary section on the line 1—1 of Fig. 2;

Fig. 2 is a sectional view taken substantially on the line 2—2 of Fig. 1;

Fig. 3 is an enlarged fragmentary view of the grate guide and lining support;

Fig. 4 is a section of the line 4—4 of Fig. 3;

Fig. 5 is a fragmentary side view of the upper rear corner portion of the incinerator showing the damper for regulating the outlet from the combustion and drying chambers; and

Fig. 6 is an enlarged fragmentary section showing the arrangement of the gas burner.

Referring to the drawing, the reference numeral 1 indicates the casing which may be of any suitable construction, preferably rectangular in horizontal section, said casing being closed by a bottom wall 2 and support-

ed by the feet 3. The upper end of the casing 1 is closed by a cover plate 4 which is secured to the casing and has an inclined front with a large opening 5 closed by a door 6, hinged to the cover plate 4 as at 7.

The door 6 affords access to the drying compartment which is located in the upper part of the casing, and has the inclined front and rear walls 8 and 9 respectively, which extend between the side walls of the casing and incline downwardly to a grate 10 which is supported in guides 11, which are secured to the side walls of the casing 1, and said grate 10 may be shifted back and forth in said guides to shake the grate or dump the contents of the drying compartment into the combustion chamber. For operating the grate 10, the latter has a stem 12 adjacent each end and long enough so that when the grate is in the normal position closing the bottom of the drying compartment, said stems project through apertures 13 provided therefor in the front wall of the casing 1, and a bail 14 has the ends of its arms pivoted to the outer extremities of the stems 12 so that it may be dropped down to a position wherein the arms of the bail are in line with the stems 12. When in this position the bail may be operated to slide the grate 10 rearwardly in the guides 11 and open the bottom of the drying compartment so as to dump the contents of the drying compartment into the combustion chamber therebelow, and when the grate 10 is again drawn forwardly by means of the bail 14, the latter may be swung upwardly and held in the upraised position by engagement with a latch 15.

The guides 11 also serve to support fire brick 16 which form the side walls of the drying compartment, the said guides being provided for this purpose with a top ledge 17 having upstanding ears 18 along the inner edge and spaced from the respective side wall of the casing to hold the lower edges of the tile or firebrick 16 therebetween.

These guides 11 may be supported in any convenient manner as for example by bolts 19 engaging through the side walls of the casing and the guides, and the latter may have recesses 20 at intervals therealong to 100

receive the nuts of the bolts 19 and avoid interference thereof with the sliding of the grate.

The combustion chamber, which is located directly below the drying compartment, is of substantially the same construction as the drying compartment and has the front and rear walls 21 and 22 respectively which extend between the side walls of the casing and converge downwardly to the grate 23 which is supported in guides 24. The guides 24 may be constructed and mounted in the same manner as the guides 11 and support fire brick 25 which form the side walls of the combustion chamber. The grate 23 may be operated in any desired manner, as by the bail 26, which is connected to stems 27 on the grate 23 and may be released from a latch 28 and dropped down to a horizontal position to shake or shift the grate 23 in the same manner that the grate 10 is operated.

For affording access to the combustion chamber the front wall of the casing 1 is provided with an opening at the upper end of the combustion chamber wall 21, closed by a door 29, and the space below the grate 23 which contains an ash pan 30, is accessible through an opening in the front of the casing closed by a door 31 and through which the ash pan 30 may be inserted and removed. This door 31 is also provided with draft openings 32 controlled by a damper 33 for regulating the draft.

For enforcing combustion of the contents of the combustion chamber a gas burner 34 is arranged along the lower edge of the wall 22 with orifices 35 at the front discharging through a space between the lower edge of the wall 22 and the grate 23, said burner 40 having the usual air mixing or intake construction at the outer end as indicated at 36 and being provided with a valve 37 for regulating the supply of gas to the burner.

The rear wall of the casing 1 near the top 45 has a smoke outlet surrounded by a flange 38 for a pipe connection, and the back wall 9 of the drying compartment extends upwardly approximately to the center of the smoke outlet, and has a ledge 39 extending 50 diametrically across the smoke outlet so that the upper portion of the latter communicates with the drying compartment, and the lower portion of the outlet communicates with the combustion chamber and thus affords 55 a draft outlet from each. For regulating the draft outlet from these chambers, a damper 40 is pivoted at the rear edge of the ledge 39 so that it may be swung upwardly to regulate or close the outlet from the drying compartment, or swung downwardly to regulate or close the outlet from the combustion chamber, said damper having a handle 41 at the side of the casing which may be arranged to counterbalance the weight of the 60 damper 40 and maintain the latter in any

position to which it may be adjusted. A deflector plate 42 is also preferably provided on the cover 4 and extending across from side to side of the drying chamber substantially as shown in Fig. 2.

For convenient operation of the door 6 through which garbage is deposited in the drying chamber, said door is provided at one end with an integral arm 43 extending beyond the side of the casing 1 and connected by a link 44 with the rear end of the pedal bar 45 which is pivoted at 46 on the base of the casing and provided with a tread portion 47 at the forward end whereby pressure of the foot on said portion 47 will rock the pedal bar 45 and through its connection with the door 6 raise the latter to the open position.

In the operation of this incinerator a fire is started in the combustion chamber. Garbage may be used for this purpose if desired, and the burner 34 ignited to dry and enforce combustion thereof. Garbage is then deposited in the drying chamber and subjected to the heat from the combustion chamber at which time the damper 40 may be adjusted, as required, to enforce circulation through the drying chamber for facilitating the drying and to carry away any odors given off as the garbage is being heated and dried. When the garbage in the drying chamber is sufficiently dried the bail 14 is released from the catch 15 which holds it in the normal upraised position, and is dropped down to the horizontal position and pushed rearwardly so as to slide the grate 10 rearwardly in the guides 11 and allow the dried garbage in the drying chamber to drop down into the combustion chamber where it serves as fuel to maintain a fire in the combustion chamber and dry any further garbage that is deposited in the drying chamber.

While I have shown and described my invention in a preferred form, I am aware that various changes and modifications may be made without departing from the principles of my invention, the scope of which is to be determined by the appended claims.

I claim as my invention:

1. In a device of the class described, the combination of a casing having two compartments therein in superposed relation with an exhaust by-pass in the casing along the exterior of the upper compartment and leading from the lower compartment to the upper end of the casing, a smoke outlet at the upper end of the casing and leading from the upper compartment and by-pass, and means for enforcing circulation through the upper compartment to the said outlet.

2. In a device of the class described, the combination of a casing having two compartments therein in superposed relation with an exhaust by-pass in the casing along the exterior of the upper compartment and leading from the lower compartment to the upper end

of the casing, a grate for each compartment, said grate for the upper compartment being slidable from a position between the compartments to a position laterally thereof in the by-pass and within the casing, a draft outlet communicating with the upper compartment and the upper end of the by-pass, and a valve for controlling communication of the upper compartment and by-pass with the draft outlet.

3. In a device of the class described, the combination of a casing having two compartments therein in superposed relation, a sliding grate between the compartments, a draft outlet communicating with both compartments, and a valve for controlling communication of both compartments with the outlet.

4. In a device of the class described, the combination of a casing having two compartments therein in superposed relation, a grate for each compartment, said grate for the upper compartment being slidable from a position between the compartments to a position laterally thereof in the by-pass and within the casing, a draft outlet communicating with each compartment and a valve for optionally interrupting communication of each compartment with the draft outlet.

5. In a device of the class described, the combination of a casing having a combustion chamber with a compartment thereabove having a rear wall inclined rearwardly and upwardly to the back wall of the casing, a grate for the compartment slidable under said wall, and a draft outlet divided by said back wall.

6. In a device of the class described, the combination of a casing having a combustion chamber and a compartment thereabove, a rear wall for the compartment, a grate slidably under said wall, a draft outlet from the casing adjacent to and divided by the upper end of said rear wall and a damper pivoted at the upper edge of said wall for controlling said outlet.

7. In a device of the class described, the combination of a casing having two compartments therein in superposed relation with a draft passageway at the side of the upper compartment, a grate for each compartment slidable to and from a position thereunder, the grate for the upper compartment being slidable from its position under said upper compartment into the aforesaid draft passageway at the side of the upper compartment, said casing having at its upper end a draft outlet with which the aforesaid passageway and the upper compartment communicate, and said casing having a draft inlet at the lower end of and communicating with the interior of the casing below the grate of the lower compartment.

EDWARD P. COLE.
